UNITED STATES PATENT OFFICE.

MARTIN A. WUEBBENHERST, OF BERRY CREEK, ALBERTA, CANADA.

WIRE-REEL.

1,068,291.

Specification of Letters Patent. Patented July 22, 1913.

Application filed September 20, 1911. Serial No. 650,356.

To all whom it may concern:

Be it known that I, MARTIN A. WUEBBENHERST, a subject of the King of Great Britain, residing at Berry Creek, in the Province of Alberta and Dominion of Canada, have invented new and useful Improvements in Wire-Reels, of which the following is a specification.

This invention relates to reels and more particularly to reels adapted for winding and unwinding rolls of wire.

The object of the invention is to provide a device of this character wherein a roll may be conveniently placed upon the reel and unwound therefrom, or a strand of wire may be wound upon the reel and tied in the form of a roll and readily removed from the reel.

A further object of the invention is the provision of a loosely journaled rim and means for holding the rim stationary with its shaft so that slack in the wire being wound or unwound may be removed from the wire.

Further objects of the invention will appear as the following specific description is read in connection with the accompanying drawings, which form a part of this application, and in which—

Figure 1 is a side elevation. Fig. 2 is a top plan view. Fig. 3 is a horizontal section through the device. Fig. 4 is a partial sectional view with the reel spokes in collapsed condition. Fig. 5 is a sectional view on the line 5—5 of Fig. 2. Fig. 6 is a perspective view showing the method of connecting the removable handle to the shaft. Fig. 7 is a detail sectional view showing the method of connecting the separate handles.

Referring more particularly to the drawings, 1 and 2 represent the separate handles of the device, the former of which is connected rigidly or forms a part of the shaft 3 which extends at right angles to the handles and has its opposite end hollow, as shown at 4, to receive the right angular end 5 of the handle 2. Adjacent the end of the shaft 3 a bayonet slot 6 is formed therein so as to receive a transverse headed stud 7 formed on the end 5 of the handle 2. The outer ends of the handles 1 and 2 are connected together by a bridge piece 8 which is permanently secured to the handle 1 and is provided with apertures 9 in its opposite end to receive the vertical pins 10 carried by the handle 2. The bridge piece is locked

upon the pin by means of thumb clamps 11 which are pivoted upon the bolt 12 passing through the handle.

Loosely journaled upon the shaft 3 is a hub 13 having a clutch face 14 and its opposite end provided with a recess 15 which is adapted to receive the inwardly turned flange 16 of a split collar 17 secured to the shaft so as to permit free rotation of the hub and at the same time prevent endwise movement of the hub upon the shaft. Projecting radially from the hub are a plurality of spokes 18 which have bearing loops 19 formed in their outer portions at spaced intervals to receive and permit radial movement of the movable roll supporting arms or rods 20. These arms or rods have formed upon their outer ends suitable crescent-shaped arms 21 upon which the wire is adapted to be wound. The inner ends of the arms have pivoted thereto, as shown at 22, one end of a toggle lever 23 whose opposite end is pivoted, as shown at 24, to the hub. The intermediate portion of each toggle lever has pivotally connected to it, as shown at 25, a link 26 whose opposite end is pivotally connected to a sliding collar 27 held in adjusted position upon the shaft by means of an adjusting collar 28 held in adjusted position upon the shaft by means of a screw or pin 29 adapted to enter the holes 30 formed in the shaft. Slidably mounted upon the opposite side of the shaft, adjacent the member 1, is a clutch member 31 having a clutch face to engage the clutch face 14 of the hub and being normally spring pressed into engagement with the hub by a spring 32 which surrounds the operating link 33 and is bridged between ears 34 and 35 formed respectively upon the member 31 and upon the shaft 3.

The operating rod, after passing through the lug 35, is pivotally connected to one end of a bell crank lever 36 pivoted at 37 upon the axle and being connected to a handle operated bell crank 38 by a link 39. The bell crank 38 is beveled so as to be engaged by the operator's hand in manipulating the device and is normally held down against the handle so as to contract the clutch member 31 and prevent its engagement with the clutch face 14. When it is desired to key a wheel to the axle 3 the hand is released from the bell crank and the spring 32 carries the clutch into engagement on the clutch face upon the hub, the clutch member 31 be-

ing prevented from rotation on the shaft by a staple 40 which is passed through a shaft and has its yoke or connecting portion raised above the shaft and operating in a 5 groove 41 formed in the clutch member.

In the operation of winding the wire upon the reel so as to form a roll thereof the wire is secured in any suitable manner to one of the arms 21 and the reel propelled along the 10 ground so as to wind the wire in circular form, the clutch member being disengaged from the clutch face 14. If it is desired to take up slack the clutch member is permitted to engage the clutch face 14 and the 15 operator simply backs, pulling upon the reel handle. After the roll has been wound thereon it is tied at suitable intervals to hold it in shape and the pin 29 is removed from the inner hole and moved outwardly 20 upon the shaft, so as to permit the collapsing of the rods 20 and arms 21 by pulling the collar 27 outwardly to the collar 28. The handle 2 is then disengaged by first disconnecting the clamps 11 and dropping the 25 handle so as to disconnect the pins 10 from the apertures 9 and the stud 7 from the

transverse portion of the bayonet slot. The end 5 is then slipped out of the end 4 in the shaft and the roll of wire can be readily removed. The reverse of this operation is carried out when it is desired to place a roll upon the arms 21.

Having thus described the invention, what I claim as new is:—

A wire reel comprising a pair of handles, a shaft mounted upon the forward ends of said handles, a hub fixed to the shaft between the handles, a series of spokes connected with the hub and provided with spaced eyes, rods slidable through said eyes 4 and having curved outer ends, a sleeve adjustable on the shaft, means for adjusting the sleeve on the shaft, toggle links pivoted to said sleeves and to the inner ends of said rods, and links pivotally connecting the hub 4 and said toggle links.

In testimony whereof I affix my signature in presence of two witnesses.

MARTIN A. WUEBBENHERST.
